UNITED STATES PATENT OFFICE.

CARL G. PETERSON, OF WEST DULUTH, MINNESOTA, ASSIGNOR OF ONE-HALF TO DAVID E. SEASHORE, OF WEST DULUTH, MINNESOTA.

RAILWAY-TIE.

No. 892,300.

Specification of Letters Patent. Patented June 30, 1908.

Application filed June 1, 1907. Serial No. 376,760.

To all whom it may concern:

Be it known that I, CARL G. PETERSON, a citizen of the United States, residing at West Duluth, in the county of St. Louis and State of Minnesota, have invented new and useful Improvements in Railway-Ties, of which the following is a specification.

This invention relates to improvements in railway ties and means for securing the rails on the ties and it consists in the construction, combination and arrangement of devices hereinafter described and claimed.

One object of my invention is to provide a railway tie of improved construction which may be made from a single sheet of metal.

A further object is to combine with the tie an improved form of rail securing devices.

In the accompanying drawings, Figure 1 is a perspective view of the railroad tie and rail-way rail securing devices embodying my improvements. Fig. 2 is a vertical longitudinal sectional view of the tie. Fig. 3 is a perspective view showing a modified form of the tie. Fig. 4 is a detail perspective view of one form of my improved rail securing device. Fig. 5 is a similar view showing another form of the same. Fig. 6 is a transverse sectional view of the form of tie shown in Fig. 3. Fig. 7 is a detail perspective view showing another modified form of rail securing device. Fig. 8 is a perspective view showing another modified form of railway tie and also showing another modified form of rail securing device. Fig. 9 is a detail longitudinal, horizontal sectional view of the form of tie shown in Fig. 8, taken on the plane indicated by the line *a—a*, of Fig. 8. Fig. 10 is a detail perspective view of the form of rail securing device shown in connection with the tie in Fig. 8. Fig. 11 is a perspective view showing another modified construction of the tie, and Fig. 12 is a detail perspective view of one of the angle pieces for strengthening the upper web of the tie.

Referring first to the form of my invention shown in Figs. 1 and 2, the tie 1 is made of a single sheet of metal bent in channel form to provide an upper or tread web 2 and vertically depending side webs 3. The tread web is formed near its ends with openings 4, from the outer ends of which integral portions of the said web are down-turned to form angle brace pieces 5 which bear between the side webs 3.

On the horizontal upper tread web 2 of

the tie are rail securing plates 6—7 to respectively bear against the inner and outer sides of the rails 8. Each plate 6 is formed with an opening 9 from the outer side of which an arm 10 which is integral with the said plate, is bent up, to engage and bear upon the inner base flange of one of the rails. Each plate 7 is formed at its inner end with an integral arm 11 to engage the outer base flange of a rail, and having its sides turned at right angles to provide flanges 12 which bear against the outer side of the web of the rail and also bear on the outer base flange and under the outer side of the head thereof. The said plates 6 and 7 are secured on the tie by means of bolts 13.

In Fig. 5, I show a modified construction of rail securing plate in which the plate 14 has an arm 15 bolted on the upper side thereof, as at 16, and with one end raised, as at 17 to bear on a base flange of a rail.

In the form of my invention shown in Fig. 3, the tie 18 comprises a pair of channel members 19 each of which has a vertical web 20, an upper web 21 and a lower web 22. The vertical webs of the respective channel members bear against each other and each of the said webs has an opening 23 therein and an integral angle piece 24 bent out from one side of said opening and extended through the opening of the vertical web of the other angle piece and bearing between the upper and lower webs of such other angle piece to brace such webs and hence strengthen the construction of the tie. The said channel members are here shown as secured together by bolts 25.

In the form of my invention shown in Fig. 8, the tie 26 is made from a single sheet of metal bent to form an upper tread and connecting portion 27 and a pair of channel members 28, each of which comprises a vertical web 29, an upper web 30 and a lower web 31. Each of the said vertical webs has an opening 32 and each of the side webs is further provided with an integral angle piece 33 bent out from one side of said opening, which passes through the opening of the vertical web of the other channel member and bears between the upper and lower flanges of such other channel member. In connection with this form of my improved tie, I also show rail securing devices 34 which are identical with the form of rail securing device shown in Fig. 7, and hereinbefore described,

with the exception that each of said devices 34 is formed with down-turned side portions forming flanges 35 which engage the common edges of the connecting tread piece 27 and the upper webs of the channel members.

5 In the form of my invention shown in Fig. 11, the tie 36 is rolled or cast, is channeled on opposite sides and comprises the vertical web 37, the head 38 and the base 39. Angle 10 pieces 40, shown in detail in Fig. 12, are placed with their horizontal arms 41 bolted to the undersides of the head and their vertical arms 42 extending through the head flanges to the base flanges of the tie.

15 Having thus described the invention, what I claim as new and desire to secure by Letters Patent is:—

1. A railway tie made of channel metal and having an opening in one web spaced 20 from one end and an integral bent portion turned angularly from one side of said opening and disposed between other webs of the tie to brace the same.

2. A railway tie comprising a pair of chan-

nel members each having a vertical web and 25 horizontal upper and lower webs, the vertical web of each member having an opening, and an angle brace piece extending through the opening and between the upper and lower webs of the other channel member.

3. A railway tie made of a single sheet of 30 metal bent to form a pair of channel members disposed side by side, each having a vertical web and horizontal upper and lower webs, and a connecting portion on and between the upper webs of the said channel members, the vertical web of each channel member having an opening spaced from one 35 end and an angle piece bent from said vertical web and extending through the opening and between the upper and lower webs of the other channel member.

In testimony whereof, I affix my signature in presence of two witnesses.

CARL G. PETERSON.
